Primary Examiner — Angela J Lee(74) *Attorney, Agent, or Firm* — Head, Johnson & Kachigian, P.C.(57) **CLAIM**

The ornamental design for a light assembly, as shown and described.

DESCRIPTION

FIG. 1 is a perspective view of a light assembly showing my new design;

FIG. 2 is an alternate perspective view thereof;

FIG. 3 is a top view thereof;

FIG. 4 is a front view thereof;

FIG. 5 is a bottom view thereof;

FIG. 6 is a right side view thereof;

FIG. 7 is a rear view thereof; and,

FIG. 8 is a sectional view taken along section line 8-8 of FIG. 4.

The left side view is a mirror of the right side view shown in FIG. 6.
